UNITED STATES PATENT OFFICE.

ROY H. SHANE, OF QUINTER, KANSAS.

VALVE.

1,308,118.

Specification of Letters Patent. Patented July 1, 1919.

Application filed April 25, 1917. Serial No. 164,527.

To all whom it may concern:

Be it known that I, ROY H. SHANE, a citizen of the United States, residing at Quinter, in the county of Gove, State of Kansas, have invented certain new and useful Improvements in Valves; and I do hereby declare the following to be a full, clear, and exact description of the invention, such as will enable others skilled in the art to which it appertains to make and use the same.

This invention relates to improvements in valves and particularly to valves for oil burners of cooking or heating stoves.

The principal object of the invention is to provide a valve by means of which the flow of oil to the burner can be more effectively regulated.

Another object is to provide a device of this character which is simple in construction, comparatively cheap to manufacture and which is easy and effective in its operation.

Other objects and advantages will be apparent from the following description when taken in connection with the accompanying drawing.

In the drawing:

Figure 1 is a side elevation of my improved valve,

Fig. 2 is a horizontal longitudinal section on the line 2—2 of Fig. 1, the needle being removed.

Fig. 3 is a vertical section on the line 3—3 of Fig. 1, and

Fig. 4 is a vertical longitudinal sectional view through the valve, the needle being in closed position.

Referring particularly to the accompanying drawing, 10 represents the body of the valve which has the longitudinal bore 11 formed therethrough, the outer end of which tapers as at 12, to receive the correspondingly shaped pin 13 of the valve stem or needle 14, which snugly and rotatably moves in the bore. The valve has two nipples 15 and 16 for connection respectively with pipes leading from the oil supply and to the burner respectively.

Leading from the nipple 15 and opening into the bore 11 is a flat or shallow passage

17, this passage greatly retarding the flow of oil into the bore 11. The stem of the valve is provided with the usual hand wheel 18 and is threadedly engaged in a stuffing box 19.

It will be particularly noted that the point of the valve stem controls the opening and closing of the tapered end of the bore and at the same time, by reason of its snug fit in the bore moves longitudinally across the channel 17 so as to gradually uncover and cover the inner end of this passage. By reason of this movement of the stem across the inner end of the passage 17, a more perfect control of the flow of oil can be had than with the ordinary needle valve, in which oil immediately starts to flow through the bore of the valve when the point is raised from its seat to the slightest degree, while with the present device oil does not start to flow until the stem partly uncovers the inner end of the channel or passage 17. Furthermore, it will be noted that the passage 17 will be closed before the point of the valve stem is seated in the tapered end of the bore whereby said pointed end will drive out of the valve any oil which might be therein.

What is claimed is:

A valve including a casing having oppositely arranged and aligned threaded nipples, a nipple formed on the casing and projecting between the first-named nipples, the casing having a longitudinal central circular bore opening at its ends through the first-named nipples, said bore communicating with the projecting nipple by a narrow flat passage, one end of the bore being formed with a tapered seat, and a pointed valve stem disposed in the bore and arranged to engage with said tapered seat, the side of the said stem covering and controlling said flat passage, the pointed end of the said stem being arranged to be seated and unseated to control the flow of fluid through the adjacent nipple and the flat passage.

In testimony whereof, I affix my signature, in the presence of two witnesses.

ROY H. SHANE.
